WALL PAPER REMOVING APPARATUS

Filed Oct. 19, 1927

FIG. 1.

FIG. 2.

INVENTOR.

Joseph Bauer
BY Miller & Boyken
ATTORNEYS.

UNITED STATES PATENT OFFICE.

JOSEPH BAUER, OF SAN FRANCISCO, CALIFORNIA.

WALL-PAPER-REMOVING APPARATUS.

Application filed October 19, 1927. Serial No. 227,148.

This invention relates to the removal of wall paper from walls preparatory to repapering of the walls, or the removal of kalsomine and similar coatings from walls.

5 The objects of my invention are to provide apparatus by which old wall paper or kalsomine may be quickly and thoroughly removed with minimum of labor cost.

The removal of old wall paper is a very 10 laborious job, costing in fact more than the work of applying new paper. Also the removal of old kalsomine requires a great deal of manual labor and the slopping of water all over the place.

15 With my apparatus herein described one man can accomplish as much work as several men by the old water and scraping process, and also do much better work as the old material comes away from the wall so easily 20 that all danger of gouging the walls is overcome.

In the drawings Fig. 1 is a perspective view of my wall paper removing apparatus as arranged ready for work, and Fig. 2 is an 25 enlarged vertical section through the same.

Briefly described my apparatus comprises a special chamber adapted to be placed open 30 side against the wall and of a steam hose connecting the chamber with a source of steam such as a steam radiator in the building being worked on, and whereby the wall 35 may be steamed for any desired length of time by holding the steaming chamber thereagainst, and moving it from place to place as the paper is softened and loosened.

35 Other features of my apparatus above described provide for removal of condensed water, and a scraping edge is provided so that the softened paper may easily be removed thereby.

In the drawings 1 is the steaming chamber 40 comprising a light sheet metal box provided with a heat insulating handle 2 at the rear side. The box is open in front and provided 45 with a laterally extending flange 3 around the face of the box adapted to seat against the wall and sometimes fitted with a rubber or other soft edging as at 4 to form a better seal.

50 Across the open face of the box is a piece

of wire mesh 5, and extending upward through the lower side of the box is a pipe connection 6 adapted for connection to a steam hose 7, a valve 8 being positioned on the line adjacent the box so that an operator 55 can control or shut off the steam at will.

Within the box are preferably arranged a few slanted louvers as at 9, while at one corner is an outlet drain connection 10 adapted for connection to a small hose 11 extending 60 to the floor and emptying into a suitable receptacle as at 12.

The upper end of the box is fitted with an adjustable scraper or plow 13 secured in place by means of thumb-screws 14 extending 65 through slots 15 in the base of the plow, so that the cutting edge can be adjusted to and from the wall as may be desired.

In operation the hose 7 is connected to a source of steam such as a steam radiator 16 70 in a building, and the chamber 1 is pressed against the wall and moved from place to place with valve opened to the required extent.

Condensation is conveyed rearward by the 75 louvers and the water discharged through hose 11.

The paper comes away freely from the wall with little scraping, frequently falling off in large pieces, and the screen 5 prevents 80 the interior of the device from becoming choked with loosened material.

For refractory wall coatings such as varnished or painted wall papers, it is merely necessary to give the device plenty of steam 85 and hold it in place a trifle longer when all will be loosened, and for the removal of old kalsomine its operation is a revelation to all who have laboriously scrubbed and scraped off this material, as it literally dissolves and 90 runs off.

Having thus described my invention, I 95 claim:

1. Apparatus of the character described comprising an open sided box forming a 95 steaming chamber adapted for positioning the open side against a wall for steaming the same, a handle on the chamber, and a steam line connection to the same, said chamber provided with a wall scraping edge 100

mounted on the upper end of the box operative against the wall above and outside of the box.

2. Apparatus of the character described comprising an open sided box forming a steaming chamber adapted for positioning the open side against a wall for steaming the same, a handle on the chamber, and a

steam line connection to the same, said chamber provided with a flange around its open side and a wall scraping edge positioned outside of the box overlying said flange and provided with means whereby it is adjustable to and from the wall. 10

JOSEPH BAUER.
